UNITED STATES PATENT OFFICE

106,789

DESIGN FOR A PENCIL

Harald F. Gade, Philadelphia, Pa., assignor to
Standard Pressed Steel Co., Jenkintown, Pa.,
a corporation of Pennsylvania

Application December 18, 1936, Serial No. 66,628

Term of patent 7 years

To all whom it may concern:

Be it known that I, Harald F. Gade, a citizen of the United States, residing in Philadelphia, Pennsylvania, have invented a new, original, and ornamental Design for a Pencil, of which the following is a specification, reference being had to the accompanying drawing, forming part thereof, in which:

Figure 1 is a view in elevation, and

Fig. 2 is a plan view of a pencil, showing my new design.

The characteristic features of my design reside in a pencil of the configuration shown, having a screw threaded cap portion, of substantially the same length as the tip portion, overhanging the lower part of the pencil, the intermediate barrel section presenting a smooth surface and the cap having a hexagonal recess in the end thereof.

I claim:

The ornamental design for a pencil, substantially as shown and described.

HARALD F. GADE.
